R. A. CLARKE

INDUCTION COIL AND MOUNTING THEREFOR

Filed August 15, 1924

FIG. 1.

Inventor
Ralph A. Clarke

By
Harrington & Mason
Attorneys.

UNITED STATES PATENT OFFICE.

RALPH A. CLARKE, OF WORCESTER, MASSACHUSETTS, ASSIGNOR TO STANDARD RADIO CORPORATION, OF WORCESTER, MASSACHUSETTS, A CORPORATION OF MASSACHUSETTS.

INDUCTION COIL AND MOUNTING THEREFOR.

Application filed August 15, 1924. Serial No. 732,200.

This invention relates to an improved induction coil and mounting for use in radio apparatus, and is particularly directed to the mechanical safeguarding of the coil 5 winding.

One of the objects of this invention is to provide a protective system for inductance coils which renders them free from danger of mechanical abrasion, or of short circuiting 10 by contact with loose leads within the apparatus.

Other objects of this invention will be apparent in the course of the following specification.

15 In the accompanying drawings—

Fig. 1 represents a plan of the exterior of one of my improved coil mounts and protectors;

Fig. 2 is a cross section on the line 2—2 20 of Fig. 1, fastened to a baseboard;

Fig. 3 is a plan of a coil mount and protector having a number of taps.

It is well known that in radio apparatus as constructed at the present time, the inductance coils employed must be made very compact and must fit in closely confined spaces 25 in order to reduce the total size of the cabinet to within reasonable limits.

One of the types of inductances capable 30 of use in such apparatus for short wave lengths is that known as the spider web coil. This comprises a supporting mount of insulating material having an odd number 35 of circumferentially spaced arms, and the inductance wire is wound successively in and out of these arms, to produce the spider web effect. This coil has the advantage of separating the turns of wire having a great difference of potential; in this way 40 large capacitive effects are avoided, as these are known to vary with the difference in potential and the distance of separation of the several turns. It has, however, the great disadvantage of not being mechanically rigid 45 in its construction, and of being very much subject to mechanical abrasion by implements used in construction. This abrasion gives rise to short circuits between the turns themselves, or even to short circuits between 50 the wires of the several turns, and another conductor in the apparatus.

To avoid these difficulties in the present apparatus, two face plates 2 and 3 are disposed on opposite faces of the coil support 1.

These plates have a succession of holes 4 55 in alinement with the corresponding holes 4' in the mount 1 for the spider web coil. The bolts 5 are passed through these holes and are provided with the preferably non-magnetic spacing washers or nuts 6 to maintain the face plates at a distance from the turns of wire 7. The ends of the coil are appropriately brought to the bolts and clamped in place, to permit the bolts to act as terminals for the coil. A central hole 60 10 is provided in each of the face plates in alinement with a hole 10' in the mount 1, for fastening the assembly to a panel or baseboard 11.

In constructing a coil and mount of this 70 type for a super heterodyne apparatus, the inductance coil 7 must be provided with several taps to enable a connection to the grid and plate of the oscillating tube, or for tapping off in tuning the primary circuit. This 75 apparatus is particularly adapted for use in such circuits by bringing the tap wires 7' to the respective bolts and securing them by clamping. The ends of the bolts are provided with binding screw-heads 8, to enable 80 connection of the assembled coil in the circuit.

It is preferable, in order to facilitate assembly of the set to mark the face plate 2 with indicia 9 to indicate the proper connections in the circuit. 85

I claim:

1. In a mount for an inductance coil, a pair of face plates coaxial with and parallel to the coil, spacing means between said plates 90 and said coil, clamping means passing through said plates and said coil to hold the same in invariable rigid relation, the ends of the winding of said coil being electrically connected to individuals of said clamping 95 means, and terminal connections on said clamping means external to said plates.

2. In an inductance unit, a supporting spider having a coil thereon, a pair of face plates mounted coaxial with and parallel 100 to the said spider, spacing washers for separating said plates and said coil, clamping bolts passing through said spider, said plates, and said washers, said bolts serving as terminals for said unit, and electrical connections established between said winding and said bolts between said plates. 105

3. In an inductance, a coil having a plu-

rality of windings with taps from the ends of the windings, a support for said coil, a face plate parallel to said support and held in spaced relation therewith, metallic clamping means passing through said support and said plate to hold the same in invariable relation, the number of said clamping means being greater than the number of windings

in said coil, said taps being connected each to one of said clamping means, and terminal connectors on said clamping means external to said plate. 10

In testimony whereof, I affix my signature.

RALPH A. CLARKE
